UNITED STATES PATENT OFFICE.

FERY LORÁNT, OF BERLIN-FRIEDENAU, GERMANY.

CHIN REST FOR VIOLINS.

Application filed July 1, 1922, Serial No. 572,332, and in Germany July 11, 1921.

My invention relates to improvements in chin rests for violins, and the object of the improvements is to provide a chin rest which is equipped with an exchangeable pad or 5 cover adapted when applied to the body of the chin rest to cover the whole surface of the body and the members for fixing the same to the violin, so that the said parts do not get in contact with the linen and the chin 10 of the musician, and a new pad or cover can readily be put in when the old one is dirty.

In order that my invention be more clearly understood an example embodying the same has been shown in the accompanying drawing in which the same reference characters have been used in all the views to indicate corresponding parts. In said drawings,

Fig. 1, is a cross-section of the chin rest 20 with the pad attached thereto,

Fig. 2, is a plan view of the pad, and

Fig. 3, is a perspective view of the chin rest with the pad attached thereto.

As shown in the drawing, my improved 25 chin rest consists of a plate *a* having a concaved top face and adapted to be clamped or otherwise secured to the violin *b* by means of a clamping member *c* connected with the plate. As shown the member *c* 30 consists of two arms made in two sections, the sections *d*¹ having axial bores and receiving therein the sections *d*² which are fixed in a position corresponding to the dimension of the belly of the violin by 35 screws *e*.

In the example shown in the drawing the cover consists of a pad *f* adapted to cover the surface of the body *a* and to be pulled around the inner margin thereof, as is 40 shown in Fig. 2, and a tongue *g* of a size sufficient to cover at least the upper part of the clamping members *d*¹, *d*². To the pad *f* a looped rubber band *h* is attached.

For applying the cover to the chin rest the 45 pad *f* is placed on the body *a* and a tongue *g* over the clamping members *d*¹, *d*², whereupon the looped rubber band *h* is pulled rearwards and placed over the tongue *g*. Thereby the inner part of the pad *f* is pulled 50 around the margin of the body *a* and below the same, and the loop holds the tongue *g* in position on the clamping members *d*¹, *d*².

Preferably, the pad is made from absorbent antislipping material such as soft gauze having a filling of cotton or the like and giving the chin a firm and soft hold on the rest. 55

The pad can readily be applied to or removed from the body of the chin rest for placing thereon a new one. This is an important advantage over chin rests having no pads secured thereto and over chin rests having pads rigidly secured thereto, because such chin rests are soiled after some time of use and therefore soil the face or 60 linen of the musician. By attaching the pad to the body of the chin rest in the manner described and by making the same with an antislipping soft surface, the musician has 65 a secure hold with his chin on the violin. 70

While in describing the invention reference has been made to a particular example embodying the same, I wish it to be understood that my invention is not limited to the construction shown in the drawing, and that 75 various changes may be made in the construction of the pad within the scope of my invention.

I claim:

1. A chin rest for violins, comprising a 80 body adapted to be placed over the belly of a violin and having means for securing the same to said belly, and a cover provided with a flexible band for removably attaching the same to said body.

2. A chin rest for violins, comprising a 85 body adapted to be placed over the belly of a violin and having means for securing the same to said belly, and a pad provided with a flexible band for removably attaching the 90 same to said body.

3. A chin rest for violins, comprising a 95 body adapted to be placed over the belly of a violin and having a holding member in position for extending over the rim of the belly and for being fixed to said belly, a cover placed over said body and holding member, and a band for holding the cover and extending from the portion thereof placed on said holding member to the opposite end thereof.

4. A chin rest for violins, comprising a 100 body adapted to be placed over the belly of the violin and formed with a holding mem-

ber adapted to be put over the rim of the belly of the violin and for being fixed to said belly, and a cover removably placed over the said body and holding member with the end opposite to said holding member around the margin of said body and having a loop secured to the end which is opposite

to the portion to be placed over the holding member and looped over the portion of the cover placed on the holding member.

10

In testimony whereof I hereunto affix my signature.

FERY LORÁNT.
